UNITED STATES PATENT OFFICE.

AUGUSTE JOSEPH DOSTERT, OF WINNIPEG, MANITOBA, CANADA, ASSIGNOR OF ONE-HALF TO JOSEPH PIERRE TREMBLAY, OF WINNIPEG, MANITOBA, CANADA.

CONVERTIBLE TABLE.

1,214,019.

Specification of Letters Patent. Patented Jan. 30, 1917.

Application filed May 3, 1916. Serial No. 95,186.

To all whom it may concern:

Be it known that I, AUGUSTE JOSEPH DOSTERT, citizen of the Dominion of Canada, residing at the city of Winnipeg, in the Province of Manitoba, in the Dominion of Canada, have invented certain new and useful Improvements in Convertible Tables, of which the following is a specification.

My invention relates to tables more particularly useful in apartment blocks, hotels and vessels, where such are required only at certain hours of the day, while a large seating capacity is in demand at all times, and the object of the invention is to provide a device which may be used as a table at meal hours and thereafter be readily converted into a plurality of chairs. The means by which this change is accomplished will be found fully described in the following specification and then more particularly pointed out in the appended claims, reference being also had to the accompanying drawings which form a part hereof and in which similar characters of reference refer to similar parts throughout the different views.

In these—Figure 1 is a plan view of the device with the parts thereof positioned to form a table. Fig. 2 is a section taken substantially on the line 2—2 in Fig. 1. Fig. 3 is a side elevation of the device with the parts positioned to form chairs. Fig. 4 is a sectional side elevation of one of the chairs. Fig. 5 is a front elevation of the same. Fig. 6 is a view of one of the corner pieces that occupy the spaces between the chairs and complete the contour of the table top. Fig. 7 is a plan view of the rotatable casting to which the chairs are hinged. Fig. 8 is a plan view of the lower casting by which the radial chair supports are carried. Fig. 9 is a view of the under side of the central portion of the table top and its maintaining member. Fig. 10 is the lever by means of which the central portion of the table top is raised to allow of the rotation of the chairs to lower the same.

In the drawings 3 indicates the base of the structure, preferably a casting having openings therearound at spaced distances for the reception of the ends of the legs 4, the latter being provided with caster wheels 5 of any preferred type. The base 3 may also be provided with a caster wheel support if such be

considered necessary, but the application is self evident and does not require illustration. 55

The base 3 is bored in two dimensions, the smaller to provide a socket for the reception of the lower end 6 of the table leg 7 and the larger to provide a space 8 around the said leg 7 to receive a ring 9 rotatably therein, 60 balls 10 being preferably disposed in the space 8 below the ring to avoid friction.

The leg 7 is provided at the top with a cap 11 forming a support for the central portion 12 of the table top, the said portion having 65 secured thereto a rectangular member 13 which passes slidably down through an opening of similar shape formed through the leg 7 and projects slightly below the same. The shape of the member 13 and of the opening through which it passes prevents any rotary movement of the portion 12 of the table top.

A lever 14 having a toe 15 engaged in a depression 16 countersunk in the lower end 75 of the member 13 provides a suitable means for raising and lowering the member 13 and with it the portion 12 of the table top when occasion demands it, the lever 14 being fulcrumed at the point 17 and having a vertical member 18 connected thereto and passing up through one of the legs 4 upon which foot pressure may be exerted to operate the lever. A coiled spring 19 is positioned around the member 18 to maintain the lever 85 in normal position.

The leg 7 is exteriorly screw-threaded as shown and a casting 20 having a bore 21 to fit the leg 7 is interiorly screw-threaded to engage the threads on the leg and is mounted thereon, the cap 11 limiting the upward movement of the casting 20 on the leg 7. 90

The casting 20 is provided with wings 22 extending out to meet the chairs 23 a plurality of which are arranged radially around 95 the leg 7, the ends of the wings 22 being apertured and the chair backs 24 being provided with members 25 which are apertured to register with the apertures in the wings to receive the rods 26 and form a hinge connection adapted to allow of a vertical rotation of the chairs upon the rods. 100

Clips 27, spaced apart to form pairs, are secured to the bottom 28 of each chair, and clips 29 are formed on the ring 9 the latter 105 also being spaced to provide intervals for

the reception of the ends of the radius rods 30 and 31 pertaining to each seat, the rods being pivoted thereto and to the clips on the seats to connect the same.

5 It will be observed that the radius rods 30 and 31 diverge as they leave the ring 9, so that the chair seats are supported at each side.

The central portion 12 of the table top 10 is preferably square and the lower edges thereof beveled back as shown at 32, the lower ends of the chair backs 24 being oppositely beveled at 33 so that when these are in horizontal position the bevels thereon 15 match with the beveled portion of the portion 12 of the top.

When the parts are in the position shown in Fig. 2, that is to say, when the casting 20 is elevated into contact with the cap 11 20 on the leg 7 of the table, the backs 24 of the chairs are in horizontal position and form part of the table top, triangular pieces 35 being positioned to fill the angles between the same and complete the contour 25 of the table top.

As it is necessary that the pieces 35 be removable the edges of the chair backs 24 are provided with grooves 36 to receive the tongues 37 formed on the edges of the said 30 triangular pieces 35. When in the position described the device provides a table having a top formed from the central portion 12, the backs 24 of the chairs and the triangular pieces 35, the said top being of any pre- 35 arranged size and shape.

When it is desired to convert the table into chairs the corner pieces 35 are removed and pressure applied upon the pedal member 18 to elevate the portion 12 of the table 40 top, thus unlocking the chairs 23 and allowing them to be rotated around the leg 7, the rotative movement being participated in by the casting 20, the ring 9 and the radius rods 30 and 31. As the movement continues 45 the casting 20 descends upon the leg 7 carrying with it the chairs 23 the seats 28 of the latter being gradually forced into horizontal position by the changing position of the radius rods 30 and 31. When the casting 50 20 reaches the portion of the leg 7 where the screw-thread ends, the movement is complete and the table has become a plurality of chairs, as shown in Fig. 3.

In Figs. 3 and 5 it will be noticed that 55 the edges of the chair bottoms 28 are provided with longitudinal grooves 39 and the corner pieces 35 are now positioned with their tongues 37 engaged in the said grooves 39, thus forming shelves between the chairs 60 for the reception of books or other articles. The positioning of the corner pieces 35 between the chairs also serves to lock the same in their new position which cannot be changed without the removal of the said 65 corner pieces.

The corner pieces may be upholstered on one side which side may be uppermost when the pieces are in their last named position thus increasing the seating capacity of the device.

70 40 in the several views indicates the arms of the chairs.

From the foregoing description it will be seen that my device provides in compact form, a piece of furniture very suitable for the purpose for which it is designed and that the number of chairs which it may be made to provide is not limited to the number shown in the drawings but may be increased to any reasonable number by increasing the size of the article.

75 It will be further understood that this specification is intended to be descriptive rather than exhaustive and that I claim as mine any variation of the means shown as 80 can be properly construed as coming within the spirit of the invention or within the scope of the appended claims.

What I claim is—

1. A table having a leg, a plurality of 90 chairs radially disposed around the leg, means connecting the chairs and leg, and operative to position the chairs to form the top of the table.

2. A table having a leg, a plurality of 95 outwardly facing chairs disposed about the leg, means connecting the chairs and leg, and operative to elevate the chairs and position them to form the top of the table.

3. A table having a leg, a plurality of 100 outwardly facing chairs radially disposed around the leg, and means operative to elevate and simultaneously rotate the chairs to position the backs thereof to form the table top.

4. A table having a leg, a plurality of 105 outwardly facing chairs radially disposed around the leg, means movably mounted on the leg and pivotally connected to the chairs to elevate the same, and means to simultaneously rotate the chairs to cause the backs thereof to assume a position constituting them a part of the table top.

5. A table having an exteriorly screw-threaded leg, a member mounted on the leg and interiorly screw-threaded for engagement with the threads thereon and having wings, a plurality of outwardly facing radially disposed chairs pivotally connected to the said wings, a member rotatively 110 mounted on the leg adjacent the bottom thereof, and radius rods pivotally connecting the chairs and rotatively mounted member.

6. A table provided with a comparatively 115 small vertically movable top having a plurality of sides and a leg by which it is supported, chairs equal in number to the sides of the top radially arranged around the leg, means operatively connecting the chairs and 120

- leg and movable thereon to elevate and rotate the chairs simultaneously whereby the backs thereof are brought into coincidence with the plane of the table top and the 5 lower edges of the backs into contact with the sides of the said top, and members shaped to fill the spaces between the backs of the chairs to complete the contour of the enlarged table top.
- 10 7. A table having a vertically movable top and a leg upon which it is normally supported, a plurality of chairs normally faced out radially around the leg, means to elevate and simultaneously rotate the chairs to 15 cause the backs thereof to assume positions as part of the table top, lever means to release or lock the chairs in their last named
- position through movement of the vertically movable portion of the table top, and members shaped to fill the spaces between the 20 chairs and provided on their edges with means adapted to interengage with means on the edges of the chairs whereby they may be positioned to complete the contour of the table top when the chairs are in elevated 25 position or to form shelves between the chairs when the latter are in normal position.

In testimony whereof, I affix my signature in the presence of a witness.

AUGUSTE JOSEPH DOSTERT.
